burgh, Pa., a corporation of Pennsylvania

Application January 12, 1946, Serial No. 640,838

7 Claims. (Cl. 200—82)

1

This invention relates to fluid pressure operated circuit breakers, and more particularly, to the control valve means for controlling the operation of such a circuit breaker.

Fluid pressure operated circuit breaker equipments designed for use in controlling high tension power circuits generally involve heavy movable parts which must be constructed and arranged for rapid operation. Compressed air at relatively high pressure, which may approximate 300 pounds per square inch, is frequently employed as the power medium for actuating circuit breakers of this type. Such a circuit breaker may be equipped with a heavy spring for effecting rapid opening of the contact elements, and a piston subject to compressed air for closing the contact elements, the completed assembly being preferably capable of effecting an open-close-open operation within a time interval of less than 17 cycles for certain classes of 60 cycle service. Because of the power and speed of operation thus required for a circuit breaker of this class, it is desirable to provide an operating mechanism having maximum simplicity and ruggedness of design, but nevertheless adapted for smooth and relatively shock-free operation.

In the construction of a circuit breaker of the above type, in order to prevent development of excessive shock and vibration during operation of the powerful actuating piston, it has been proposed to control the supply of compressed air in such a manner as to insure relatively smooth and safe acceleration of the piston, particularly during initial movement. For this purpose there has been provided a control valve means functioning to restrict or reduce the rate of supply of compressed air to the piston cylinder during initial movement of the piston, and designed to move quickly from a throttling position to an open position for permitting quick final buildup in pressure, following a predetermined initial movement of the piston, preferably at the start of compression of the accelerating spring or other load such as at the point in its traverse corresponding to the initial touching of the contact elements of the circuit breaker. In this way, the piston is prevented from acquiring such a velocity as might result in undesired slamming during operation of the circuit breaker, while full operating force becomes available for overcoming any resistance to final closing of the breaker contact elements. In the co-pending application of James M. Cumming, filed April 21, 1945, Serial Number 589,581, now Patent Number 2,434,549, granted January 13, 1948, for example, there is

2

disclosed a circuit breaker having a control valve means embodying a positive latch for holding the control valve means in its throttling position against the force of a spring, together with means for releasing the latch at the proper time, including a plurality of interlocking levers.

It is the object of my invention to provide a new and improved control or throttle valve mechanism of the above type, in which rugged and simple features of construction are combined to promote positive operation and to minimize the effect of friction on the speed of operation of the mechanism.

Another object of the invention is to provide an improved throttle valve mechanism embodying a minimum number of operating parts, thus facilitating installation of the mechanism in a circuit breaker equipment of existing design.

Other objects and advantages of the invention will appear in the following more detailed description thereof, taken in connection with the accompanying drawings in which:

Figure 1 is a diagrammatic view, partly in section, of the operating portions of a fluid pressure operated circuit breaker equipment having associated therewith a preferred form of control valve mechanism constructed in accordance with the invention;

Fig. 2 is a fragmentary sectional view taken partly on the line II—II of Fig. 3 of the control valve mechanism shown in a closed position corresponding to the open position of the circuit breaker; and

Fig. 3 is a sectional view taken substantially along the line III—III of Fig. 2.

Referring to the drawing, in Fig. 1 there is illustrated in diagrammatic form a portion of a single pole unit of a fluid-pressure-operated circuit breaker, comprising a suitable frame structure (not shown) supporting stationary contact elements 5 in the power circuit to be controlled, a movable resilient contact element 6 cooperative therewith and secured to a rod 7, a cylinder 10 having mounted therein an operating piston 11, and a piston rod 12, the upper end 13 of which is pivotally connected to the rod 7 through the medium of a beam 14 fulcrumed on a stationary pin 15. A coil spring 17 is mounted in cooperative relationship with the movable contact element 6 for urging that element toward an open circuit position. The piston 11 is responsive to the pressure of air admitted to a pressure chamber 20 for actuating the piston rod 12, beam 14 and rod 7 to move the contact element 6 into circuit closing engagement with the stationary

contact elements 5, in opposition to the force exerted by opening spring 17 and resilient contact element 6.

For maintaining the circuit breaker elements just described in circuit closing position, the circuit breaker apparatus is further provided with a transversely disposed beam 22, one end of which is journaled on a pin 23 carried by a link 24 that is in turn pivotally connected to a pin 25 carried by the frame structure. The beam 22 is operatively connected by means of a pin 28 to the piston rod 12 at a point above the cylinder 10, and also carries, at the end opposite the pin 23, a roller 30 which is adapted to be engaged by a suitable latch mechanism, generally indicated as 31, for holding the beam 22 and the associated elements of the circuit breaker in the circuit closing position, as shown in Fig. 1.

The latch mechanism 31 may be of any suitable design and, as illustrated, comprises a main latch member 32 journaled on a stationary pin 33 secured to the frame structure, a release pawl 34 pivotally connected to the frame structure by means of a pin 35 for cooperation with the latch member 32, and an auxiliary latch member 36 adapted for cooperation with the pawl 34. The main latch member 32 has a surface 38 adapted for latching engagement with the roller 30, and an extension 40 adapted for interlocking engagement with a portion of the pawl 34 for resisting clockwise movement of the main latch member about pin 33 under the force tending to raise the end of the beam 22 carrying the roller, and thus ending to effect disengagement of the latch member 32 from the roller. For biasing the main latch member 32 in a counter-clockwise direction, there is provided a spring 42, which is interposed between a suitable lug on the frame structure and the head of a link pivoted to the latch member.

For tripping the latch mechanism 31, there is provided a trip coil 44, which is adapted to be energized through the medium of a suitable trip control circuit (not shown) for causing upward movement of an armature carrying a plunger 45 that is operatively aligned with a portion of the pawl 34. The pawl 34 is normally urged into the position shown in Fig. 1 by means of a spring 47, which is adapted to yield upon operation of the pawl by the trip plunger 45. The auxiliary latch member 36 is inoperative when the parts are positioned as shown in Fig. 1, but serves to hold the pawl 34 out of interfering engagement with latch member 32 when the beam 22 and other operating elements of the circuit breaker are in circuit opening position. A coil spring 49 is interposed between a portion of the cylinder structure 11 and a lug 50 on the auxiliary latch 36, and acts to tilt the latter in a clockwise direction about pin 35, causing the lug 50 to carry the pawl 34 in the same direction, when the end of the beam 22 carrying roller 30 is swung upwardly during a circuit breaker opening operation. It will be noted that a lug 51 carried on the upper end of auxiliary latch 36 is adapted to be engaged by the free end of the beam 22, when that beam is moved to the circuit closing position as shown in Fig. 1. With the auxiliary latch member 36 thus held down, the spring 47 is permitted to maintain the pawl 34 in interlocking engagement with the main latch member 32.

For controlling the supply of fluid under pressure to the chamber 20, there is provided a magnet valve assembly, generally indicated at 55, comprising a casing having a valve chamber 56

communicating with a fluid supply pipe 57, which may be connected to any suitable source of fluid under pressure. Within chamber 56 is mounted an inlet valve 58 for controlling communication from the valve chamber to a passageway 60 leading to the pressure chamber 20. The supply valve 58 is normally urged toward a seated position by a coil spring 62 mounted in the valve chamber 56, and is provided with a valve stem 63 which extends upwardly and terminates in an armature portion (not shown) movably disposed within a magnet coil 65 carried by the frame structure. The magnet coil 65 is adapted to be energized through the medium of a suitable control circuit (not shown) which may be arranged in any approved and well known manner for insuring the desired automatic operation of the circuit breaker equipment. The valve stem 63 also carries a discharge valve element 67 which is operative to vent the passageway 60 to atmosphere when the supply valve element 58 is in its seated position, as shown in Fig. 1. Upon energization of the magnet coil 65, the stem 63 is shifted downwardly to close the valve element 67 while opening the supply valve 58 to effect supply of fluid under pressure to the pressure chamber 20 above the piston 11.

It is not deemed necessary to illustrate the control circuits for the magnet coils 44 and 65, but it will be understood that any suitable circuit breaker controlling system may be provided to furnish the usual features of automatic operation well known in the circuit breaker art. For example, the trip coil 44 may be arranged for energization in response to development of a fault in the main circuit controlled by the circuit breaker, or alternatively to be subject to manual control. If the circuit breaker equipment includes means for effecting a quick automatic reclosing operation following an opening operation in response to a fault, the circuit for energizing the magnet coil 65 may be arranged to initiate energization thereof instantaneously upon tripping of the circuit breaker apparatus or soon thereafter, to thus insure a subsequent reclosing operation with minimum loss of time.

According to the invention, a throttle valve assembly, indicated generally by the reference character 70, is provided for controlling the rate of supply of fluid under pressure through the passageway 60 to the piston chamber 20 at a rate determined in accordance with the operation of the circuit breaker. The throttle valve assembly includes a casing portion 71 carried on the cylinder 10, and having a suitable bore 73 disposed substantially vertically and in intersecting relation with respect to a passage 76 communicating through a pipe 77 with the passageway 60. As shown diagrammatically in Fig. 3, passageway 76 extends through the casing section 61 and wall of cylinder 10 to the piston chamber 20. A restricted bypass 74 is formed in the casing section 71, as is best shown in Fig. 3, for permitting flow of fluid around the bore 73 at a rate determined by adjustment of a screw-threaded valve element 75. Slidably mounted in the vertical bore 73 is a valve element 78, which is urged downwardly under the force of a coil spring 79 that is interposed between the lower end of the valve element and a cap 80 carried by the casing section 71 and secured thereto by suitable means, such as bolts 82. With the valve element 78 held in its lowermost position, as shown in Fig. 1, the passageway 76 is maintained open so that flow 75 of fluid under pressure is virtually unrestricted.

On the other hand, when the valve element 78 is shifted to its uppermost position, as is best shown in Fig. 2, flow of fluid under pressure is limited to the flow area of the bypass 74.

The throttle valve element 78 is arranged for operation in accordance with operation of the piston rod 12 and associated elements of the circuit breaker. For this purpose the valve element 78 has secured thereto a stem 90 which extends upwardly through the bore 78 and through a suitably packed aperture in the cap member 80, the upper end of the stem carrying a clevis member 91. The parallel walls of clevis member 91 are apertured to receive a pin 92 to which is pivotally connected a movable, substantially vertically aligned latch member 94. The latch member 94 has a lug 95 disposed thereon just below a sloping cam surface 96, which is adapted to be urged into engagement with a roller 97 journaled on a pin 98 carried by a pair of upwardly extending arm portions 100 of the cap members 80. Only one of the arm portions 100 is illustrated in the sectional views included in the drawing. A small spring 102 is interposed between an upper flat surface of the clevis member 91 and a lower corner surface of the latch member 94 for biasing the latch member toward the roller 97. Also operatively aligned with the cam surface 96 of the latch member 94 is an extension of the pin 28 which, as already explained, operatively connects the beam 22 to the piston rod 12.

For providing a lost motion connection between the clevis member 91 and the beam 22 of the circuit breaker mechanism, there is provided a bifurcated link member generally indicated by reference character 110, which preferably comprises spaced parallel portions, joined at the upper and lower ends, only one of these portions being represented in the drawing. The lower end of the link member 110 is pivotally connected to the pin 92 between the spaced portions of clevis member 91. The link member 110 has formed therein an elongated slot 112 into which both the end of pin 28 and the roller 97 are adapted to extend, as indicated in Fig. 1 of the drawing. Mounted on the uppermost end of the link member 110 is a set screw 115 which may be adjusted and locked in place by means of a lock nut 116, to provide means for limiting the traverse within the slot 112 of the pin 28 carried by beam 22. When the beam 22 is tilted to the open position of the circuit breaker, as indicated in Fig. 2, the pin 28 engages the end of the set screw 115 to lift the link member 110, stem 90 and valve element 78.

In operation, if the circuit breaker equipment is disposed in its circuit closing position, as shown in Fig. 1, the beam 22 is held in a substantially horizontal position with the roller 97 in latching engagement with the main latch member 32, so that the circuit breaker is held positively in the circuit closing position against any force tending to open the contact elements 5 and 6. At the same time the spring 79 is effective to hold the throttle valve element 78 in its lower or open position, as shown in Fig. 1, while the latch member 94 is also disposed in its lowermost or unlatched position, with the lug 95 thereof located beneath the roller 97.

If it is desired to effect an opening operation of the circuit breaker, the magnet coil 44 is energized through the medium of the usual controlling circuit, as already explained, whereupon the plunger 45 is quickly raised to disengage the

pawl 34 from the main latch member 32. Due to the relatively small area of contact between the inclined surface 38 of the main latch member and the roller 97, the spring 42 is unable to resist the slight clockwise movement of the latch required to release the beam 22 and the latter is consequently moved upwardly about pin 28, while rod 12, beam 14, and rod 7 are at the same time actuated by the spring 17 to effect disengagement of the contact element 6 from the contact elements 5.

The piston 11 is carried upwardly during the upward movement of the piston rod 12 but if the circuit breaker is equipped for a quick automatic reclosing operation, the operation of the usual auxiliary reclosing means (not shown) results in energization of the magnet coil 65 in time to operate the supply valve 68 for admitting compressed air to the piston chamber 20 before piston 11 has reached its uppermost position. Upon the resultant supply of compressed air to chamber 20, the upward motion of the piston 11 will thus be reversed prior to any engagement between pin 28 and to the set screw 115 mounted on the upper end of the slotted link member 110. The throttle valve element 78 thus remains in its full open position to insure substantially unrestricted flow of compressed air through passageway 60, pipe 77, and passageway 76 to pressure chamber 20, to furnish the maximum force needed for reversing the movement of the mechanism and causing quick reclosure of the circuit breaker.

If the fault in the controlled circuit has not been removed at the time when the reclosure of the circuit breaker occurs, the trip coil 44 will again be energized and coil 65 will be deenergized for venting the piston chamber 20 to atmosphere, thereby rendering spring 17 again operative to open the circuit breaker. It will be understood that suitable dump valve means may be provided for augmenting the discharge of compressed air from piston chamber 20 in order to promote quick upward movement of piston 11. One form of such dump valve and a suitable control circuit for the complete mechanism is shown in Patent No. 2,361,178, issued October 24, 1944 to James M. Cumming, and assigned to the assignee of the present application. For the purpose of disclosing the present invention, however, it is deemed unnecessary to show such a dump valve and control circuit in the drawing.

Assuming that the circuit breaker is moved to its circuit opening position with the contact element 6 held out of engagement with contact elements 5 under the force of spring 17, it will be apparent that the beam 22 will be moved to the position illustrated in Fig. 2 of the drawing. At this time, the operating piston 11 will be moved to its uppermost position within cylinder 10, while the pin 28 carried by the piston rod 12 and beam 22 will be carried into engagement with the set screw 115 for raising the link 110, stem 90 and valve element 78 to the throttling position as illustrated in Fig. 2. As the latch 94 is at the same time carried upwardly, the lug 95 thereof is caused to ride over the roller 97 and then to engage that element under the force exerted by spring 102, so that the valve element 78 will then be latched in its upper or throttling position to limit the communication between the passageway 60 and piston chamber 20 to the flow area of the bypass 74.

If the controlling circuit for the circuit breaker is now energized in the usual manner to cause

a closing operation, the consequent energization of the magnet coil 65 of the magnet valve device 55 effects unseating of the supply valve element 58 against the force of spring 62, while discharge valve 67 is moved to its seated position. Compressed air is then supplied from the usual source by way of pipe 57, valve chamber 56, past the unseated valve element 58, thence through passageway 60, pipe 77 and restricted bypass 74 to the piston chamber 20. The piston 11 is thereby moved downwardly by the pressure of air for operating the rod 12, beam 14 and rod 7 to bring the movable contact element 6 toward the contact elements 5.

It will be understood that although sufficient compressed air is quickly supplied by way of the communication just described, including the restricted bypass 74, to effect prompt closing movement of the associated circuit breaker operating elements, the increase of pressure of fluid in chamber 20 is nevertheless so controlled as to prevent the piston 11 and other movable elements from acquiring an excessive velocity during the initial operation. As the piston 11 continues its downward movement, the pin 28 carried by piston rod 12 engages the cam surface 86 of latch member 84 and forces the latter to the left, as viewed in Fig. 1, so that the lug 88 is released from the roller 97. The spring 70 is thereby rendered effective to shift the assembled valve element 78, stem 90, latch member 84 and link member 110 downwardly. The exact point at which the pin 28 releases the spring-pressed valve element 78 may be varied somewhat by proper adjustment of the stem 90 with respect to the valve element 78, it being observed that a lock nut 120 is attached to the lower threaded end of the stem for fixing these elements in the desired position.

With the valve element 78 thus shifted to its open position substantially instantaneously, the supply of compressed air to the piston chamber 20 is continued at a suddenly increased rate of flow, and the air pressure in chamber 20 is thus increased quickly so that sufficient force is exerted on the piston 11 to effect final movement thereof to the fully closed position of the circuit breaker, regardless of any increase in resistance to such movement that might be caused during final closing operations of the contact elements 6 and 5.

From the foregoing it will be seen that an improved control valve mechanism constructed in accordance with my invention may be assembled from a minimum number of sturdy yet inexpensive operating elements, which are adapted to operate smoothly and without substantial variation in speed due to friction or other cause. The control valve assembly is readily accessible for inspection or repairs, and may easily be adjusted to insure its operation at the desired instant in the cycle of operation of the circuit breaker mechanism.

Having now described my invention, what I claim as new and desire to secure by Letters Patent is:

1. In a fluid pressure operated circuit breaker having relatively movable contact means, a cylinder, piston means operative upon an increase in fluid pressure in said cylinder for moving said contact means to a circuit closed position, and means for moving said contact means to an open circuit position, the combination of supply valve means operative to supply fluid under pressure through a communication to said cylinder, throttle valve means interposed in said communica-

tion and having an element movable between a position for restricting flow therethrough and an open position for permitting maximum flow, means for biasing said movable throttle valve element toward open position, a positive latch pivotally mounted on said movable throttle valve element and engageable with a fixed part for releasably holding said throttle valve element in the restricting position, a member movable by said piston means for moving said throttle valve element against its bias, and said member engaging and releasing said latch during movement of said piston means prior to movement of said throttle valve element.

2. In a fluid pressure operated circuit breaker having relatively movable contact means, a cylinder, and movable abutment means operative upon an increase in fluid pressure in said cylinder for moving said contact means, the combination of supply valve means operative to supply fluid under pressure through a communication to said cylinder, throttle valve means interposed in said communication having a position for restricting flow therethrough and an open position for permitting maximum flow, means for biasing said throttle valve means toward one position, a positive latch for holding said throttle valve means in the other position, a pin and slot lost motion connection between said movable abutment means and said throttle valve means for moving said throttle valve means against said biasing means to locked position when the pin engages one end of the slot, and said pin engaging said latch before reaching the other end of the slot for releasing said latch prior to any movement of the throttle valve means toward said one position.

3. In a fluid pressure operated circuit breaker having relatively movable contact means, operating mechanism including a cylinder, a piston operative upon an increase in fluid pressure in said cylinder for moving said contact means to a circuit closed position, and means for moving said contact means to an open circuit position, the combination of supply valve means operative to supply fluid under pressure through a communication to said cylinder, throttle valve means interposed in said communication having a position for restricting flow therethrough and an open position for permitting maximum flow, means for biasing said throttle valve means toward open position, a latch element movable with said throttle valve means and also movable relative thereto, a stationary element engageable by said latch element for releasably holding said throttle valve means in the restricting position, and a link member connected to actuate said throttle valve means and having lost motion cooperation with a movable part of the operating mechanism, and said movable part of the operating mechanism engaging and moving said latch to unlatched position upon predetermined movement of said contact means toward the closed circuit position.

4. A fluid pressure operated circuit breaker having contact means movable to open circuit position and to closed circuit position, an operating cylinder, a piston operative upon supply of fluid under pressure to said cylinder for moving said contact means, fluid pressure control means including a passage for supplying fluid under pressure to said cylinder, valve means biased toward one position and movable to another position to control the rate of flow of fluid under pressure through said passage, a latch pivotally connected to said valve means for at times lock-

ing same in said other position against the bias thereon, a link pivotally connected to said valve means at the pivot of said latch and being movable in response to movement of said contact means in one direction for shifting said valve means against its bias, and a member movable relative to said link in response to movement of said contact means in the opposite direction for releasing said latch means.

5. A fluid pressure operated circuit breaker having contact means movable to open circuit position and to closed circuit position, an operating cylinder, a piston operating upon supply of fluid under pressure to said cylinder for moving said contact means, fluid pressure control means including a passage for supplying fluid under pressure to said cylinder, valve means biased toward an open position and movable to a throttling position to control the flow of fluid under pressure through said passage, a latch operative to hold said valve means in throttling position and having a cam surface thereon, a link having a lost motion connection with said piston for shifting said valve means to throttling position so as initially to reduce the rate of supply of fluid under pressure to said cylinder during subsequent movement of said contact means from the open circuit position, and an element movable with said piston along said link to engage the cam surface and release said latch after said piston has been moved through a predetermined portion of a circuit closing stroke.

6. A fluid pressure operated circuit breaker having contact means movable to open circuit position and to closed circuit position, an operating cylinder, a piston operative upon supply of fluid under pressure to said cylinder for moving said contact means to closed circuit position, a member operative with said piston, spring means operative to move said contact means to open circuit position, fluid pressure control means including a passage for supplying fluid under pressure to said cylinder, a valve biased toward an open position and movable to a throttling position to control the flow of fluid under pressure through said passage, an element mounted on said cylinder, a positive latch releasable by said member and cooperative with said element for at times holding said valve in throttling position, and link means cooperative with said member

5 and connected to said valve for shifting it to the throttling position to reduce the rate of flow of fluid under pressure to said cylinder during initial movement of said contact means from the closed circuit position, said link means having a slot receiving said member and constituting a lost-motion connection between said member and said valve, and said member in the slot engaging said latch near one end of the slot so that said piston must almost complete a contact closing stroke prior to effecting operation of said latch to released position.

10 7. In a fluid pressure operative circuit breaker of the type including movable contact means, 15 means for moving said contact means to an open circuit position, a movable abutment operative upon an increase in the pressure of fluid in a chamber for moving said contact means to a closed circuit position, and supply valve means operative to supply fluid under pressure to said 20 chamber, the combination therewith of throttle valve means interposed between said supply valve means and said chamber, said throttle valve means including a spring and a movable valve element biased by said spring toward an open 25 position for permitting supply of fluid to said chamber at a maximum rate, a latch pivotally connected to said movable valve element, stationary means engageable with said latch for releasably holding said throttle valve means in a 30 throttling position to reduce the rate at which fluid under pressure can be supplied to said chamber, link means having a lost-motion operative relation to said movable abutment for effecting 35 movement of said valve element to the throttling position only when said abutment is shifted to a position corresponding to the open circuit position of the contact means, and means operative with said movable abutment to engage and release said latch upon a predetermined movement 40 of said abutment for closing said contact means.
